Patented July 6, 1976

240,433

ELECTRIC SHAVER BATTERY CHARGING STAND

Jacob A. Krapowicz, Ridgefield, Conn., assignor to
Sperry Rand Corporation, Bridgeport, Conn.

Filed Feb. 24, 1975, Ser. No. 552,631

Term of patent 14 years

Int. Cl. D13—02; D28—03

U.S. Cl. D26—15 B

Fig. 1.

Fig. 2.

Fig. 3.

Fig. 4.

Fig. 5.

Fig. 6.

FIG. 1 is a perspective view of the front and left side of an electric shaver battery charging stand showing my new design;

FIG. 2 is a top plan view of the charging stand of FIG. 3;

FIG. 3 is an elevational view of the front of the charging stand of FIG. 1;

FIG. 4 is a bottom plan view of the charging stand of FIG. 3;

FIG. 5 is an elevational view of the left side of the charging stand of FIG. 1; and

FIG. 6 is an elevational view of the right side of the charging stand of FIG. 1.

I claim:

The ornamental design for an electric shaver battery charging stand, substantially as shown.
